UNITED STATES PATENT OFFICE.

KRAFT BOOTH, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR AN ARTIFICIAL-LIGHT SHADE.

40,891.

Specification for Design. Patented Sept. 20, 1910.

Application filed July 23, 1910. Serial No. 573,585. Term of patent 14 years.

To all whom it may concern:

Be it known that I, KRAFT Booth, a citizen of the United States, and resident of the city and county of Philadelphia and State of Pennsylvania, have invented a new, original, and ornamental Design for an Artificial-Light Shade, of which the following is a specification, reference being had to the accompanying drawing.

In said drawing Figure 1 is a perspective

view and Fig. 2 a top or plan view of an artificial light shade showing my new design.

I claim—

The ornamental design for an artificial light shade, as shown.

KRAFT BOOTH.
